UNITED STATES PATENT OFFICE.

AUGUST E. WENDT, OF THORPE, WISCONSIN.

RADIATOR FOOT-REST.

1,149,880.

Specification of Letters Patent. Patented Aug. 10, 1915.

Application filed December 17, 1914. Serial No. 877,695.

To all whom it may concern:

Be it known that I, AUGUST E. WENDT, a citizen of the United States, residing at Thorpe, in the county of Clark and State 5 of Wisconsin, have invented certain new and useful Improvements in Radiator Foot-Rests, of which the following is a specification.

The present invention relates to a foot 10 rest attachment for radiators, and has for its object to provide a device of this character which embodies novel features of construction whereby it may be readily attached to a radiator of any conventional construction and quickly adjusted to any desired position thereon.

A further object of the invention is to provide a device of this character which is comparatively simple and inexpensive in its 20 construction, which can be applied to a radiator without necessitating alterations in the construction thereof, and which may be used either as a foot rest or as a support for articles which it may be desired to heat or 25 dry.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in 35 which:—

Figure 1 is a side elevation of a radiator provided with a foot rest attachment constructed in accordance with the invention. Fig. 2 is an end view of the same, the attachment being shown by full lines as arranged at the bottom of the radiator so as to be used as a foot rest, and by dotted lines as applied to the top of the radiator so as to be used as a rack for the support of 45 articles to be dried or heated. Fig. 3 is a horizontal sectional view through one end of the radiator on the line 3—3 of Fig. 1, showing the corresponding end of the foot rest attachment in normal position thereon.

Fig. 4 is a similar view showing the supporting wing of the attachment as swung upwardly into a substantially vertical position preparatory to detaching from or applying the attachment to the radiator. Fig. 5 is a 55 detail perspective view of one of the supporting wings and the corresponding end of

the supporting lever. Fig. 6 is a detail perspective view of one of the supporting levers. Fig. 7 is a detail perspective view showing a modification in which the wing is welded 60 to the supporting lever.

Corresponding and like parts are referred to in the following description and indicated in all the views of the drawing by the same reference characters.

Specifically describing the present embodiment of the invention, the numeral 1 designates a radiator of the conventional type, said radiator being formed of a series of spaced loops 2 which are arranged to 70 provide the usual vertically elongated passage 5 which extends through the radiator from end to end. The attachment is supported by means of a pair of wings or plates 6 which have a greater width than the passage 5 of the radiator and are inserted into the passage from opposite ends thereof. Projecting from each of the wings 6 is a supporting lever or arm 7, the inner ends of the said levers being rigidly connected to 80 the wings 6 while the outer ends thereof carry the foot plate or support 8. With this construction it will be obvious that the weight of the foot plate will operate through the levers 7 to swing opposite edges of the wings 6 into a binding engagement with the sides of the longitudinal passage 5 of the radiator. In other words the wings 6 will be bodily rotated until the opposite longitudinal edges thereof are caused to firmly engage 85 the sides of the radiator passage 5. As soon as the wings 6 thus become firmly wedged in position they provide a support for the remainder of the attachment. The outer ends of the supporting levers 7 terminate in 90 the downwardly projecting extensions 7^a which are hinged at 10 to a rod 11. The axes of the hinged connections 10 at opposite ends of the rod 11 are disposed at right angles to the axis of the said rod and under 100 normal conditions are substantially horizontal. The inner end of each of the supporting levers 7 terminates in a laterally projecting arm 7^b which is arranged at substantially right angles to the extension 7^a 105 and is rigidly connected to the corresponding wing 6. In the preferred construction each of the wings is provided with a sleeve 14 which extends along one side thereof intermediate of its edges and loosely receives 110 the lateral arm 7^b of the corresponding supporting lever. A set screw 15 is threaded in

one side of the sleeve 14 so as to engage the lateral arm 7^b of the supporting lever 7 and lock the said members rigidly in an adjusted position.

- 5 The foot plate 8 has one edge thereof loosely connected to the rod 11 while the opposite edge thereof is adapted to be swung rearwardly into engagement with the radiator. Ordinarily this foot plate 8 will assume an inclined position, as indicated more clearly by Figs. 1 and 2 of the drawing. The outer end of each of the supporting levers 7, at the upper end of the downward extension 7^a, may be secured by a suitable fastening member such as the screw 16 to the adjacent edge of the foot plate 8 so as to lock the members in operative position. The extensions 7^a at the outer ends of the supporting levers 7 then project downwardly and are substantially vertically disposed, while the lateral arms 7^b at the inner ends of the supporting levers project inwardly and are substantially horizontally disposed. When thus positioned, as has been 20 previously explained, the weight of the foot plate 8 acting upon the outer ends of the supporting levers 7 tends to rotate the wings 6 within the passage 5 of the radiator and force opposite edges of the wings into a binding engagement with the sides of the said passage so that the wings become firmly wedged in position and serve as a support for the entire attachment. It will thus be obvious that the wings may be wedged in 25 position within the passage 5 at any desired elevation upon the radiator. When it is desired to use the attachment merely as a foot rest, it would be positioned at the bottom of the radiator, as indicated by full lines upon Fig. 2, while when it is desired to use the attachment as a rack to support articles which it may be desired to dry or warm, it would be applied to the top of the radiator as indicated by dotted lines on Fig. 2.
- 30 45 Preparatory to applying the attachment to a radiator or removing it therefrom, the screws 16 are removed so that the supporting levers 7 can be swung outwardly about the hinges 10 as pivots. The extensions 7^a are thus brought into a substantially horizontal position with the lateral arms 7^b projecting upwardly in a substantially vertical position. The wings 6 are carried by the lateral arms 7^b so as to be tilted from a horizontal position to a vertical position, or vice versa, as the lateral arms are moved. When the supporting levers 7 are thus swung bodily about the hinged connections 10 as pivot centers so that the extensions 7^a assume a substantially horizontal position, the wings 6 are withdrawn from the radiator passage 5 and brought into a vertical position so that the attachment can readily be removed from the radiator. This position of the members is indicated more clearly by Fig. 4. Should it
- be desired to apply the attachment to a radiator, the wings 6 would be swung upwardly into a vertical position and the attachment positioned upon the radiator as indicated by Fig. 4. The wings 6 would then be swung downwardly into a substantially horizontal position within the longitudinal passage 5 of the radiator, as indicated by Fig. 3. The wings 6 might then be raised or lowered within the radiator passage 5 until the attachment was adjusted at the proper height, and then rotated as previously described so as to bring the longitudinal edges into a binding engagement with the sides of the radiator passage. After 75 replacing the screws 16 the various parts of the device would be held rigidly in position and any weight or force applied to the foot plate 8 would merely tend to rotate the wings 6 into a firmer engagement with the 80 radiator.
- Fig. 7 illustrates a slight modification of the invention in which the wing 6^x is shown as welded at 20 to the supporting lever 7^x. A rigid and inexpensive construction is 90 thereby obtained which can be readily constructed in the proper dimensions to fit easily in the longitudinal passage of any of the conventional types of radiators. The operation of this modified form of the invention is identical with that previously described.
- Having thus described the invention, what I claim is new and desire to secure by Letters Patent, is:-
- 100 1. A foot rest attachment for radiators, including a wing adapted to be inserted in the radiator passage, a supporting lever rigid with and projecting laterally from the wing, and a foot rest mounted upon the supporting lever so that the weight thereof acts through the lever to rotate the edges of the wing into a binding engagement with the radiator.
- 105 2. A foot rest attachment for radiators, including a wing adapted to be inserted in the radiator passage, a supporting lever projecting laterally from the wing and formed with an arm which is rigidly attached to the wing between the edges thereof, and a foot rest mounted upon the supporting lever so that the weight thereof acts through the lever to rotate the edges of the wing into a binding engagement with the radiator.
- 110 3. A foot rest attachment for radiators, including a wing adapted to be inserted in the radiator passage and formed with a sleeve arranged parallel to and between the longitudinal edges thereof, a supporting lever projecting laterally from the wing and formed with a lateral arm adjustably received within the sleeve, means for clamping the arm rigidly in an adjusted position 115 within the sleeve, and a foot rest mounted 120 upon the lever.
- 125 4. A foot rest attachment for radiators, including a wing adapted to be inserted in the radiator passage and formed with a sleeve arranged parallel to and between the longitudinal edges thereof, a supporting lever projecting laterally from the wing and formed with a lateral arm adjustably received within the sleeve, means for clamping the arm rigidly in an adjusted position 130 within the sleeve, and a foot rest mounted

upon the supporting lever so that the weight thereof acts through the lever to rotate the edges of the wing into a binding engagement with the radiator.

- 5 4. A foot rest attachment for radiators, including a pair of wings adapted to be inserted in the radiator passage from opposite ends thereof, supporting levers rigid with the respective wings and projecting laterally therefrom, a rod connecting the supporting levers and hingedly connected to the extremity thereof to admit of the outer ends of the levers and the wings carried thereby being swung into and out of the 15 radiator passage, and a foot rest mounted upon the rod so that the weight thereof acts through the levers to rotate the edges of the wings into a binding engagement with the radiator.
- 20 5. A foot rest attachment for radiators, including a pair of wings adapted to be inserted in the radiator passage from opposite ends thereof, supporting levers rigid with the respective wings and projecting laterally therefrom, downwardly projecting extensions at the outer ends of the supporting levers, a rod connecting the extremities of the said extensions and attached thereto by hinged joints having axes at right angles to 25 the axis of the rod so that the levers can be swung about the said hinged joints to shift the wings from a vertical to a horizontal position or vice versa, means for locking the levers in an operative position, and a foot 30 plate mounted upon the rod so that the weight thereof acts through the levers to rotate the edges of the wings into a binding engagement with the radiator.
- 35 6. A foot rest attachment for radiators, including a pair of wings adapted to be inserted in the radiator passage from opposite ends thereof, a pair of supporting levers each provided at one end thereof with a laterally projecting arm rigidly connected

to a corresponding wing at a point between 45 the edges thereof and at the other end thereof with a lateral extension projecting in a plane at right angles to the plane of the lateral arm, a rod connecting the extremities of the said extensions and attached 50 thereto by hinged joints having axes at right angles to the axis of the rod so that the said levers can be swung about the hinged joints to swing the wings from a horizontal position to a vertical position or vice versa, a 55 foot plate mounted upon the rod so that the weight thereof acts through the levers to rotate the edges of the wings into a binding engagement with the radiator, and means for securing the levers to the foot plate to 60 hold them rigidly in operative position.

7. A foot rest attachment for radiators, including a pair of wings adapted to be inserted in the radiator passage from opposite ends thereof, a pair of supporting levers 65 rigidly connected to the edges of the wings and arranged in planes at right angles to the planes of the wings, connecting means between the outer arms of the supporting levers, said connecting means being joined 70 to the supporting levers by hinged joints having axes at right angles to the axes of the supporting levers so that the supporting levers can be bodily swung laterally to swing the wings from horizontal positions 75 into upright positions when applying the attachment to a radiator or removing it therefrom, and a foot plate supported by the supporting levers so that pressure applied thereto acts through the levers to rotate the edges of the wings into a binding engagement with the radiator.

In testimony whereof I affix my signature in presence of two witnesses.
